SKIRT MARKER

Max Ingwer, Forest Hills, N. Y., assignor to Consolidated Sewing Machine & Supply Co. Inc., New York, N. Y., a corporation of New York

Application January 30, 1940, Serial No. 316,319

11 Claims.

(Cl. 33—9)

The herein disclosed invention relates to skirt markers.

The objects of the invention are to provide a skirt marker of as few and inexpensive parts as possible, to so design these parts that they can be quickly and easily assembled or taken apart and, with these special advantages, to have a skirt marker which will be entirely practical and desirable.

10 The various novel features of the invention by which the foregoing and other desirable objects are attained are set forth hereinafter, illustrated in the accompanying drawing and covered in the claims.

15 The drawing illustrates certain practical and at present preferred forms of the invention, but it should be understood that structure may be modified and changed as regards this disclosure, all within the true intent and scope of the invention, as defined in the claims.

20 Figure 1 is a side elevation of one of the skirt markers.

Figure 2 is an enlarged and part broken sectional view as on substantially the plane of line 2—2 of Fig. 1.

25 Figure 3 is a broken sectional view as on substantially the plane of line 3—3 of Fig. 2.

Figure 4 is a view looking at the back of the sliding clamp shown in Figure 3, with the stick or support broken away.

30 Figures 5 and 6 are views similar to Figures 3 and 4, illustrating a modified form of the invention.

Figure 7 is an enlarged sectional detail on line 35 1—1 of Fig. 1.

Figure 8 is a broken front view of the tube guide shown in Figure 7.

As shown in the general view, Figure 1, the device consists in the main of a dispensing head 10, carrying a powder holding jar 11, and slidingly engaged upon a vertical support 12. The latter is indicated in the form of a yardstick removably set in a socket 13, in a base 14.

40 The dispensing head is shown in Figs. 1, 2 and 3, as a simple block of material having an opening in the top of the same through which the pipe or tubing 15, is entered and having a screw socket 16, in the underside of the same for receiving the screw neck 17 of the powder jar. The forward edge of the block is slotted at 18, to form a thin flaring powder discharge outlet.

45 The back of the dispensing head is shown as smooth and flat at 19, to fit smoothly and slide easily over the face of the yardstick. Rearwardly projecting lugs 20, at this back portion of

the head engage the opposite edges of the stick to confine the head laterally on the stick.

5 In the first illustrated form of the invention, the rearwardly projecting guide lugs 20, are shown as bulged or rounded upwardly and downwardly at 21, to form shoulders for engagement by the C-shaped rounded end portions 22, of a clip or bracket which carries at its intermediate or bridging portion 23, between the C-shaped ends an arched spring 24, whose opposite ends 10 yieldingly bear against the back of the stick at points above and below the head structure.

15 While the spring 24 may be an integral portion of the mounting clip, it usually is the best practice to cut and shape the spring from flat strip spring stock and attach it as by rivets or other suitable fastenings 25, to the intermediate bridge portion of the separately formed clip structure.

20 For additional fastening purposes, the tips of the C-shaped portions 22, of the spring mounting bracket are shown as entering grooves 26, provided in the upper and lower faces of the dispenser head.

25 In the modification illustrated in Figs. 5 and 6, the generally C-shaped end portions 22a of the spring mounting clip are angular instead of rounded in shape, the rearwardly projecting lugs 20a are simply flat continuations of the upper and lower surfaces of the dispenser head 10a 30 and the inturned tips of the clip engage in grooves 26a and are permanently secured in this relation by rivets or similar through fastenings 27.

35 In both forms illustrated, engagement of the clip with the head is effected by simply slipping the clip endwise over the lugs projecting from the back of the ejector head. In the first form shown, separation of the clip from the head is prevented, after the head is in position on the stick, by the disposition of the C-shaped extensions at the opposite side edges of the stick, Fig. 4, and in the second form, the through fastenings 27, positively secure the clip against separation from the head. One such through fastening may be employed instead of the two shown and for general purposes, it is usually sufficient to rely upon the cooperative relation between the clip and the stick to prevent separation of the spring clip from the head.

40 The spring strip 24 is shown as placed inside the back of the mounting clip and the latter is indicated as grooved or arched outwardly at 28, to provide a groove or channel in the back of the clip for receiving and positioning the spring. 50

45

55

The pipe or tubing 15, is elastically held and sealed where it passes through the top of the dispenser head by means of a rubber or elastic grommet 29, Fig. 3. This grommet is shown as having spaced flanges engaging the upper and lower surfaces of the wall 30, forming the top of the head and an intermediate neck portion substantially filling the opening 31, through this top wall. The center opening in the grommet 10 through which the pipe or tubing passes is of a size to yieldingly grip and hold such pipe or tubing. As a consequence, the grommet is elastically held in the top wall of the head and the pipe or tubing is elastically held in the grommet 15 and consequently in the wall of the dispensing head. These parts so assembled will hold in such relation. This holding is so effective that in the case of rigid tubing, the latter may be used as a handle for shifting the dispenser head 20 vertically to different positions of adjustment on the stick.

The pipe or tubing may be guided at the top. It is here shown as extending through a loop 32, in a twisted wire guide which has its ends bent to 25 form spring jaws 33, yieldingly gripping over the opposite edges of the stick. This spring wire guide, after it is opened or spread to engage it over the end of the stick may be shifted to any 30 desired position on the stick, where it will then remain unless again shifted or removed from the stick.

The pipe or tubing is shown as entering the top of the dispenser eccentrically in relation to the jar and toward the back of the dispenser head. 35 This serves to introduce the air in the back of the jar and furthest removed from the powder discharge slot at the front and also positions the pipe or tubing as close as possible to the stick. With the pipe or tubing thus close to the face of 40 the stick, the guide need project only a slight distance from the face of the stick. This arrangement also enables the tubing, if it be a rigid connection, to serve more readily as a handle for adjusting the dispenser up and down on the 45 stick, since the shifting force is then applied relatively close to the plane of sliding engagement of the head with the stick.

Any suitable form of pressure creating means 50 may be provided, such as a simple bulb on the upper end of the pipe or tubing as indicated at 34.

In this invention, the parts are few and all of 55 simple inexpensive and sturdy design. The dispenser head is an inexpensive part, of simple design, readily molded in one piece. When molded in plastic, the discharge slit may be formed by a small circular saw cut in the front edge of the dispenser block. Assembly of the device is accomplished by simply putting the parts together 60 and once assembled their inter-engagement and relation hold them so and prevent accidental disconnection. The structure however is such that at any time the parts can be readily separated as for shipping or storage.

65 The double flanged elastic grommet seals the pipe or tubing tightly in the dispenser head, holding said tubing at the proper distance to which it has been set to extend down into the powder jar and serving as a yielding coupling 70 between the tubular connection and head when such connection is used as an adjusting handle. The slightly bowed, two armed spring by engagement with the stick, at relatively widely separated points, above and below the point of engagement of the head with the stick, holds the

head firmly in a position of adjustment, but at the same time permits the head to be readily slid upward or downward into different positions of adjustment. The powder holding jar is readily screwed up into the underside of the dispenser head, making tight joint therewith when fully screwed up into position. Actually this container 5 may be in the nature of a bottle, jar or can, made of glass, plastic, metal, wood, paper or other materials, and it may be removably connected 10 and supported by other than a screw joint, although the latter at present is preferred, because of its simple, inexpensive and positive character. The air tube 15 may be either rigid or flexible 15 in character, or partially rigid as where it enters the top of the dispenser and partly flexible.

To more positively hold or interlock the air tubing in the grommet, such tubing, particularly the rigid pipe form may be provided with a reduced portion 35, where it is held in the grommet, 20 thus to provide the shoulders 36, in engagement with the opposite ends of the grommet. Thus with this construction, the grommet will still hold the pipe even if there be some shrinkage of parts.

To positively overcome any tendency of the 25 spring wire clip from tilting on the stick, the ends of the same may be bent in opposite directions as indicated at 37, and doubled over as shown, so as to leave no rough edges.

The rearward offset in the back of the bracket 30 locates the mid portion of the spring and the heads of the rivets which hold the spring in place, so that these parts will entirely clear the ends of the lugs when slipping the bracket edge-wise into interlocked position over the lugs. 35

The opposite sides of the head may be fluted, corrugated, roughened or otherwise treated as indicated at 38, to provide finger grips by which the head may be readily held in slipping the bracket into position thereon or in some instances, for sliding the head up and down on the stick, particularly when flexible tubing is used which can not be used as a handle, as can a rigid pipe. When rubber tubing is employed, it may be fastened more securely and particularly to prevent it being pulled up out of the grommet, by forcing a somewhat oversize ferrule up inside the tubing below the grommet, thus to expand the tubing and provide in effect the equivalent of the lower shoulder 36 in Fig. 3. To assure substantially air tight fit between the jar and the powder head, a gasket or packing washer may be disposed between the upper end of the jar and the end of the screw seat. 50

What is claimed is:

1. A skirt marker, comprising in combination, 55 an upright support, a dispenser head having an opening through the top of the same, a socket in the underside of the same, a powder discharge slot in the front of the same and extending inwardly into communication with said socket, the back of said head being slidably engaged with the face of said upright support and said head having rearwardly projecting lugs spaced to extend to opposite sides of said upright support, 60 a powder holder detachably engaged in said socket and dependent from said head, air tubing entered through said opening in the top of the dispenser head, air pressure creating means connected with said tubing, a clip having substantially C-shaped end portions engaged with said rearwardly extending lugs and connected in spaced relation by a bridge portion and spring arms carried by said bridge portion and yieldingly 65

engaging the back of the upright support at points above and below said dispenser head.

2. A skirt marker, comprising in combination, an upright support, a dispenser head having an opening through the top of the same, a socket in the underside of the same, a powder discharge slot in the front of the same and extending inwardly into communication with said socket, the back of said head being slidingly engaged with the face of said upright support and said head having rearwardly projecting lugs spaced to extend to opposite sides of said upright support, a powder holder detachably engaged in said socket and dependent from said head, air tubing entered through said opening in the top of the dispenser head, air pressure creating means connected with said tubing, a clip having substantially C-shaped end portions engaged with said rearwardly extending lugs and connected in spaced relation by a bridge portion and spring arms carried by said bridge portion and yieldingly engaging the back of the upright support at points above and below said dispenser head, said socket being in the form of a substantially circular seat and said tubing being entered through the top of the dispenser head eccentrically of said seat and toward the back of said head.

3. A skirt marker, comprising in combination, an upright support, a dispenser head having an opening through the top of the same, a socket in the underside of the same, a powder discharge slot in the front of the same and extending inwardly into communication with said socket, the back of said head being slidingly engaged with the face of said upright support and said head having rearwardly projecting lugs spaced to extend to opposite sides of said upright support, a powder holder detachably engaged in said socket and dependent from said head, air tubing entered through said opening in the top of the dispenser head, air pressure creating means connected with said tubing, a clip having substantially C-shaped end portions engaged with said rearwardly extending lugs and connected in spaced relation by a bridge portion and spring arms carried by said bridge portion and yieldingly engaging the back of the upright support at points above and below said dispenser head and an elastic grommet seated in said top opening about said tubing and having spaced flanges engaging upper and lower surfaces of the top of said head, said elastic grommet being held compressed by the walls of said opening in which it is seated and compressibly gripping said tubing to thereby secure said tubing in position to extend a predetermined distance down into said powder container and forming a resilient coupling between the tubing and the head through which the tubing may be used as a handle to slide the dispenser head to different positions on the upright support.

4. A skirt marker, comprising in combination, an upright support, a dispenser head having an opening through the top of the same, a socket in the underside of the same, a powder discharge slot in the front of the same and extending inwardly into communication with said socket, the back of said head being slidingly engaged with the face of said upright support and said head having rearwardly projecting lugs spaced to extend to opposite sides of said upright support, a powder holder detachably engaged in said socket and dependent from said head, air tubing entered through said opening in the top of the

dispenser head, air pressure creating means connected with said tubing, a clip having substantially C-shaped end portions engaged with said rearwardly extending lugs and connected in spaced relation by a bridge portion and spring arms carried by said bridge portion and yieldingly engaging the back of the upright support at points above and below said dispenser head and an elastic grommet seated in said top opening about said tubing and having spaced flanges 10 engaging upper and lower surfaces of the top of said head, said elastic grommet being held compressed by the walls of said opening in which it is seated and compressibly gripping said tubing to thereby secure said tubing in position to extend a predetermined distance down into said powder container and forming a resilient coupling between the tubing and the head through which the tubing may be used as a handle to slide the dispenser head to different positions 15 on the upright support and a spring wire clip yieldingly gripped over opposite edges of said upright support and twisted in the form of a loop surrounding said tubing.

5. In a skirt marker, a substantially flat 25 horizontally extending dispenser head having a screw socket in the underside of the same, an opening through the top of the same and a horizontally extending powder discharge slit extending inwardly from the front edge of the 30 same into communication with said screw socket, said head having spaced rearwardly projecting lugs at the back of the same, a mounting bracket having forwardly projecting substantially C-shaped end portions engaged with said rearwardly projecting lugs, upwardly and downwardly projecting spring arms carried by said mounting bracket, an upright stick slidingly engaged by the back of said head and by said upwardly and downwardly projecting spring arms, a screw 40 mouth powder containing jar engaged in said screw socket and supported thereby, an elastic grommet seated in said opening in the top of the dispenser head and air conducting tubing 45 extending downwardly through and yieldingly gripped in said grommet.

6. In a skirt marker, a horizontally extending dispenser head having a screw socket in the underside of the same, an opening through the top of the same and a horizontally extending 50 powder discharge slit extending inwardly from the front edge of the head into communication with said screw socket, an upright support at the back of said head and slidingly engaged thereby, a bracket at the back of said upright support and having forwardly extending arms in interlocked engagement with the head at opposite sides of said upright support, upwardly and downwardly projecting spring arms carried by said bracket and yieldingly engaging the back of 55 said upright support at points above and below said head, a screw mouth powder container engaged in said screw socket and supported thereby, an elastic grommet compressibly seated in 60 said opening in the top of the head and air conducting tubing compressibly held in said elastic grommet and extending downwardly toward the interior of said powder container.

7. A skirt marker, comprising a generally flat 70 horizontally extending head, having a substantially horizontal slit in the front edge of the same, a smooth back portion, a socket in the underside of the same and an opening through the top, said head having shoulders at the rear- 75

ward edge portions of the same, a bracket slide-
able edgewise over the back of said head mem-
ber and having elements interlocking with said
shoulders in said edgewise shifting movement,
5 an upright support engageable by said smooth
back portion of the head, spring means carried
by said bracket in resilient sliding engagement
with the back of said upright support, a powder
container removably engaged in said socket in
10 the underside of the head and air conducting
tubing extending downward through said opening
toward the interior of said powder container.

8. A skirt marker, comprising an upright sup-
port, a marking head slidably mounted on said
15 upright support and including upwardly extending
air conducting tubing and a length of wire
twisted in a loop at the face of the support sur-
rounding said tubing and opposed jaws engag-
ing opposite edge portions of said upright sup-
port, said jaws having upwardly and downwardly
20 projecting extensions engaging the back of the
upright support to oppose tipping of said loop
at the face of the support.

9. A powder dispenser for a skirt marker, com-
25 prising a horizontally extending dispenser head
having an opening in the top of the same, a
powder discharge outlet in the front of the same
and a socket below the opening in the top, a
powder holder removably engaged in said socket,
30 a flanged elastic grommet engaged in said top
opening and air pressure tubing extending
through said grommet and having a reduced
shouldered portion disposed between the upper
and lower ends of the grommet, said grommet
35 being held compressed by the walls of the open-
ing in which it is seated and compressibly grip-
ping said reduced portion of said tubing to there-
by secure said tubing in position to extend a pre-
determined distance down into said powder
40 holder and to form a resilient coupling between
the tubing and the head, through which the
tubing may be used as a handle for shifting
said dispenser head.

10. A skirt marker, comprising in combination,
45 an upright support, a dispenser head having an
opening through the top of the same, a socket
in the underside of the same, a powder discharge
slot in the front of the same and extending in-
wardly into communication with said socket, the
50 back of said head being slidably engaged with
the face of said upright support, a powder holder
detachably engaged in said socket and dependent
from said head, air tubing entered through said

opening in the top of the dispenser head, air
pressure creating means connected with said
tubing, spring arms connected with the back
portion of said head at opposite sides of the
upright support and yieldingly engaging the back
5 of said upright support at vertically separated
points and an elastic grommet seated in said top
opening about said tubing and having spaced
flanges engaging upper and lower surfaces of the
top of said head, said elastic grommet being held
10 compressed by the walls of said opening in which
it is seated and compressibly gripping said tubing
to thereby secure said tubing in position to ex-
tend a predetermined distance down into said
powder container and forming a resilient coupling
15 between the tubing and the head through which
the tubing may be used as a handle to slide the
dispenser head to different positions on the up-
right support.

11. A skirt marker, comprising in combination, 20
an upright support, a dispenser head having an
opening through the top of the same, a socket in
the underside of the same, a powder discharge
slot in the front of the same and extending in-
wardly into communication with said socket, the 25
back of said head being slidably engaged with
the face of said upright support, a powder holder
detachably engaged in said socket and dependent
from said head, air tubing entered through said
opening in the top of the dispenser head, air 30
pressure creating means connected with said
tubing, spring arms connected with the back por-
tion of said head at opposite sides of the upright
support and yieldingly engaging the back of
said upright support at vertically separated 35
points and an elastic grommet seated in said top
opening about said tubing and having spaced
flanges engaging upper and lower surfaces of the
top of said head, said elastic grommet being held
compressed by the walls of said opening in 40
which it is seated and compressibly gripping said
tubing to thereby secure said tubing in position
to extend a predetermined distance down into said
powder container and forming a resilient coupling
45 between the tubing and the head through which
the tubing may be used as a handle to slide the
dispenser head to different positions on the up-
right support and a vertically adjustable spring
clip having an intermediate loop portion sur-
50 rounded the tubing and opposed jaws yieldingly
gripped over opposite edges of the upright sup-
port.
